GEORGE H. GILMAN, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

PNEUMATIC TOOL.

1,236,701.

Specification of Letters Patent. Patented Aug. 14, 1917.

Application filed April 22, 1908. Serial No. 428,618.

To all whom it may concern:

Be it known that I, GEORGE H. GILMAN, a citizen of the United States, and residing at Claremont, county of Sullivan, State of New Hampshire, have invented an Improvement 5 in Pneumatic Tools, of which the following description, in connection with the accompanying drawings, is a specification, like letters on the drawings representing like parts.

My invention relates to pressure-fluid tools adapted to be operated by compressed air or other elastic pressure fluid, being more particularly concerned with the provision of 15 simplified and efficient valve-controlling means therefor.

My invention will be best understood by reference to the following description when taken in connection with the accompanying 20 illustration of one specific embodiment thereof, while its scope will be more particularly pointed out in the appended claims.

In the drawings:

Figure 1 is a longitudinal, central section taken through a pneumatic hammer embodying one form of my invention and

Fig. 2 is a similar sectional view taken in a plane at right-angles to the plane of the section shown in Fig. 1.

Referring to the drawings and to the embodiment of the invention shown therein, there is provided a cylinder 1, the rear or upper end of which has threaded engagement with the hollow casing 2, the latter 35 having a closed end and acting as a housing for the rear end of the cylinder and for the valve block 3. The cylinder is prevented from accidental unscrewing by the split clamping collar 4. A portion of the handle 40 piece 5 or other member by which the tool is supported is shown, but it will be understood that the particular construction of handle forms no material part of this invention and that the same may be used with 45 various forms of handles or other supports well known in the art.

The upper end of the cylinder chamber is closed by the forward wall of the valve block 3, there being provided a valve block 50 plate or cap 6 between the upper end of the valve block and the walls of the casing 2. The cylinder, valve block and plate are

maintained in the alinement required for the registration of connecting passages by means of a dowel pin 7. The head of the 55 casing is recessed at 8 to provide a constant pressure supply chamber to which, when the tool is in use, compressed air or other pressure fluid is constantly supplied through the air inlet 9.

The valve block is of a generally cylindrical shape and has an interiorly formed valve chamber axially alined with the cylinder. The illustrated form of valve instead of moving in a direction opposite to the direction of the piston is arranged to move in the same direction with the piston, that is to say, it is arranged to move consequent upon the piston movement and in the same direction as the piston. For this purpose the enlarged 70 head 10 of the valve works in an enlarged chamber portion 11 located at the rear of the valve block and connected with the intermittent pressure passage 12 of the cylinder by the passage 13. The forward or contracted portion of the valve chamber is constantly opened to pressure fluid through the lateral passage 14 and longitudinal passage 15, the latter communicating at the upper face of the plate 6 with the constant pressure chamber 8.

The contracted portion of the valve chamber is provided with two annular chamber grooves 16 and 17, both of which are in constant communication with the rear end of 85 the cylinder (Fig. 2) through the medium of the longitudinal passage 18. In the rear-most position of the valve (Fig. 2) the forward end of the valve chamber is opened to the groove 16 and the cylinder ports 18 admitting pressure fluid thereto through the uncovering of the groove 16 by the end face of the reduced or contracted head portion 19 of the valve. In this position pressure fluid is therefore freely admitted to the rear 90 end of the cylinder. Pressure fluid is admitted to, and exhausted from, the forward end of the cylinder through a passage 20 opening into the cylinder through the port 21, the latter being located near the forward 100 end of the cylinder. The passage 20 extends longitudinally the walls of the cylinder and the valve block and communicates with the enlarged rearward portion of the valve

chamber through the passage 22. In the rearward position of the valve the passage 22 and therefore the forward end of the cylinder is opened to the exhaust through 5 the annular valve groove 23, which latter places the passage 22 in communication with the exhaust port or ports 24, the latter maintaining constant communication between the enlarged valve chamber and the 10 annular exhaust space 25, which is located between the valve block and the housing or casing 2. The latter is perforated at one or more points such as 26 and 27 so as to permit free exhaust of pressure fluid to the 15 atmosphere through the port or ports 24. The piston has the reduced portion 27 having a sliding fit within the contracted walls 28 of the cylinder, the effective area against which the pressure acts in returning the 20 piston being that provided by the shoulder formed between the contracted portion and the main body portion of the piston.

When the return piston movement has proceeded far enough to withdraw the reduced piston portion 27 from the contracted 25 cylinder walls 28, the forward end of the cylinder is placed in communication with the tool space 29, the latter being in free communication with the atmosphere through 30 the exhaust opening 30.

At the end of the forward stroke the hammer piston delivers its blow upon the shank of the tool 31, the latter held within the usual sleeve or bushing 32. During the 35 forward movement of the piston the valve is held in the position shown in Fig. 2 by the pressure acting against the smaller constant pressure area at the forward end of the valve. Near the close of the forward 40 movement of the piston the controlling valve is reversed by the admission of pressure fluid to the larger area at the rear of the valve and in the enlarged portion of the valve chamber which fluid acting against the 45 larger pressure area thereat reverses the valve against the constant pressure upon the forward end. Pressure fluid is admitted to the enlarged rear end of the valve chamber through the intermittent pressure passage 50 12, which latter is placed in communication with the constant pressure passage 33 by means of a circumferential groove 34 formed in the piston. The passage 33 opens into the cylinder through the port 35 and is adapted 55 to be connected with the port 36 opening into the passage 12. When the circumferential groove uncovers the ports 35 and 36 pressure fluid is admitted to the upper part of the chamber to move the valve forward to 60 the position shown in Fig. 1. In this position pressure fluid is cut off from the annular chamber groove 16 while the annular groove 17 is opened to the forward end of the enlarged valve chamber portion so that 65 pressure fluid is exhausted from the rear

end of the cylinder through the passage 18, groove 17, annular valve groove 23 and exhaust passage 24.

The enlarged head end of the valve is closed but the opposite end is constantly open 70 to pressure fluid, which latter is freely admitted to the interior of the valve. Communicating with the interior of the valve is one or more radial ports 37 opening through the walls of the enlarged head 10 and connecting with an exterior annular groove 38 upon the valve, the said groove being adapted to be brought into registration with the lateral passage 22 when the valve is advanced to the position shown in Fig. 1. In this position 80 of the valve therefore pressure fluid is admitted to the forward end of the cylinder to return the piston through the hollow interior of the valve, the radial ports 37, groove 38, passage 22 and return passage 20. 85

The constant pressure passage 33 opening into the cylinder is in constant communication with the live pressure passage 15 as shown in Fig. 1.

It will be evident that on the rearward 90 stroke of the piston the valve is again moved from the position shown in Fig. 1 to that shown in Fig. 2 when the second or more advanced port 39 connected with the intermittent pressure passage 12 is uncovered by 95 the piston and opened to the exhaust passage 30, this resulting in exhausting the pressure fluid from the larger area at the rear of the valve chamber and causing the pressure fluid at the forward end of the 100 valve to lift the same to the position shown in Fig. 2.

While I have herein shown and described in detail for purposes of illustration one specific embodiment of the invention, it is to be 105 understood that the same is not limited to the details shown or to the construction or relative arrangement of parts disclosed, but that extensive modifications may be made therein without departing from the spirit 110 of the invention.

What I claim and desire to secure by Letters Patent is:

1. A pressure fluid tool having a cylinder, a piston, a pressure fluid supply passage, a hollow valve provided with two heads of different diameter separated by an exterior annular groove, the end of the smaller head being open and having about its opening an annular surface constantly exposed to pressure fluid from said pressure fluid supply passage, and the end of the larger head being closed to the entrance of pressure fluid, a port connected with the rear end of said cylinder and extending across said annular 115 surface of the smaller head into direct communication with said pressure fluid supply passage, the smaller head being adapted to alternately open and close such communication across said annular surface, a port con- 120

nected to the forward end of the cylinder and adapted to be intermittently opened to the hollow interior of the valve, and an exhaust passage communicating with the space 5 about the annular groove of the valve and adapted to be placed alternately in communication with the opposite ends of the cylinder.

2. A pressure fluid tool having a cylinder, 10 a piston, a pressure fluid supply space, a hollow valve located at the rear of the cylinder and in alignment therewith, said valve being provided with two heads of different diameter separated by an exterior annular 15 groove, the end of the smaller head being open and having about its opening an annular surface constantly exposed to pressure fluid from said pressure fluid supply passage, and the end of the larger head being 20 closed to the entrance of pressure fluid, a port connected with the rear end of said cylinder and extending across said annular surface of the smaller head into direct communication with said pressure fluid supply 25 passage, the smaller head being adapted to alternately open and close such communication across said annular surface, a port connected to the forward end of this cylinder and adapted to be intermittently opened 30 to the hollow interior of the valve, and an exhaust passage communicating with the space about the annular groove of the valve and adapted to be placed alternately in communication with the opposite ends of the 35 cylinder.

3. A pressure fluid tool having a cylinder, a piston, a pressure fluid supply passage, a hollow valve provided with two heads of different diameter and having an exterior 40 annular groove, the smaller head being imperforate and the larger head being perforated by one or more lateral passages opening outward from the hollow interior of the valve, the end of the smaller head being 45 open and having about its opening an annular surface constantly exposed to pressure fluid from said pressure fluid supply passage, and the end of the larger head being closed to the entrance of pressure fluid, a 50 port connected with the rear end of said cylinder and extending across said annular surface of the smaller head in direct communication with said pressure fluid supply passage, the smaller head being adapted to 55 intermittently open and close said communication across said annular surface, a port connected to the forward end of the cylinder and adapted to be intermittently opened to the hollow interior of the valve through 60 communication with said lateral valve passage or passages, and an exhaust passage communicating with the space about the an-

nular groove of the valve adapted to be placed alternately in communication with the opposite ends of the cylinder. 65

4. A pressure fluid tool having a cylinder, a piston, a pressure fluid supply passage, a valve provided with two heads of different diameter and having an exterior annular groove, the smaller head being provided with an annular surface constantly exposed to pressure fluid from said pressure fluid supply passage and having means for admitting pressure fluid to the interior of the valve, and the end of the larger head 70 being closed to the entrance of pressure fluid, a port connected with the rear end of said cylinder and extending across said annular surface of the smaller head into direct communication with said pressure fluid supply passage, the smaller head being adapted to alternately open and close such communication across said annular surface, a port connected to the forward end of the cylinder and adapted to be placed intermittently in communication with the interior of the valve and the pressure fluid supplied therethrough from said pressure fluid supply passage, and an exhaust passage communicating with the space about the annular 80 groove of the valve and adapted to be placed alternately in communication with the opposite ends of the cylinder. 85

5. A pressure fluid tool having a cylinder, a piston, a pressure fluid supply passage, a hollow valve provided with two heads of different diameter separated by an exterior annular groove, the smaller head at the forward end of the valve being open and constantly exposed to the pressure fluid supply in said pressure fluid supply passage, and the end of the larger head being at the rear and closed and exposed to intermittent pressure, a port connected with the rear end of the cylinder and extending across the end 100 face of the smaller head of the valve into direct communication with said pressure fluid passage, the smaller head of the valve being adapted to alternately open and close such communication across the end face thereof, 105 a port connected to the forward end of the cylinder and adapted to be opened to the interior of the valve, and an exhaust passage communicating with the space about the annular groove of the valve, and adapted to be 110 placed alternately in communication with the opposite ends of the cylinder. 115

In testimony whereof, I have signed my name to this specification, in the presence of two subscribing witnesses.

GEORGE H. GILMAN.

J. A. BRUCE.

It is hereby certified that in Letters Patent No. 1,236,701, granted August 14, 1917, upon the application of George H. Gilman, of Claremont, New Hampshire, for an improvement in "Pneumatic Tools," an error appears in the printed specification requiring correction as follows: Page 3, line 107, claim 5, after the word "fluid" insert the word *supply*; and that the said Letters Patent should be read with this correction therein that the same may conform to the record of the case in the Patent Office.

Signed and sealed this 25th day of September, A. D., 1917.

[SEAL.]

F. W. H. CLAY,

Acting Commissioner of Patents.
